Primary Examiner—Philip S. Hyder*Assistant Examiner*—RoseLynne (Ulm) Cody(74) *Attorney, Agent, or Firm*—Rader, Fishman & Grauer, PLLC(57) **CLAIM**

The ornamental design for a case for electronic device, as shown and described.

DESCRIPTION

FIG. 1 is a front elevational view of a case for electronic device showing my new design;

FIG. 2 is a rear elevational view thereof;

FIG. 3 is a right side elevational view thereof, a left side elevational view thereof being a mirror image;

FIG. 4 is a top plan view thereof;

FIG. 5 is a bottom plan view thereof;

FIG. 6 is a top, right perspective view thereof;

FIG. 7 is a bottom, left perspective view thereof;

FIG. 8 is a cross-sectional view thereof taken along the line VIII—VIII shown in FIG. 1; and,

FIG. 9 is a cross-sectional view thereof taken along the line IX—IX shown in FIG. 1.
